UNITED STATES PATENT OFFICE.

ADAM C. SMITH, OF PHILADELPHIA, PENNSYLVANIA.

IMPROVEMENT IN THE CONSTRUCTION OF WASTE-WATER PIPES.

Specification forming part of Letters Patent No. 84,442, dated November 24, 1868.

To all whom it may concern:

Be it known that I, ADAM C. SMITH, of Philadelphia, Pennsylvania, have invented an Improved Waste-Water Pipe; and I do hereby declare the following to be a full, clear, and exact description of the same.

My invention consists of a water-pipe made by coiling a strip of metal spirally and so that one edge shall overlap the other, as described hereinafter, a pipe thus made being more economical than ordinary soldered pipes, and at the same time such that it will accommodate itself to the ice which frequently forms in water-pipes during the winter months.

In order to enable others skilled in the art to make and practice my invention, I will now proceed to describe a mode of carrying the same into effect, reference being had to the accompanying drawings, which form a part of this specification, and in which—

Figure 1 is an exterior view, and Fig. 2 a sectional view, of my improved waste-water pipe.

I take a long strip of tinned or galvanized-iron plate or of zinc and coil it spirally round a cylindrical former, taking care that one edge overlaps the other, as seen in Fig. 2. After the former has been withdrawn, one rivet, x , at each end of the pipe will suffice to maintain the coil in the form of a tube; or in place of a rivet a small patch of solder may be used at these points. The different lengths are fitted together in the same manner as those of ordi-

nary pipes—that is, by inserting the end of one length a short distance into the end of the other. No soldering of the joint of the spiral fold is necessary, the overlapping of the fold being such that the water cannot escape there.

Instead of a cylindrical pipe, one of a square, triangular, or of other sectional form may be made, the shape of the pipe depending upon that of the former upon which the strip of metal is coiled.

One advantage of my improved pipe is that it can expand to a limited extent and accommodate itself to the ice which frequently forms in waste-water pipes during the winter months. As no soldering is required, except it be at the extreme ends, where either patches of solder or rivets may be used, and as a comparatively cheap material may be employed in the manufacture of the pipes, they are more economical than those heretofore used.

I claim as my invention and desire to secure by Letters Patent—

A water-pipe consisting of a strip of metal coiled spirally and so that one edge shall overlap the other, as set forth.

In testimony whereof I have signed my name to this specification in the presence of two subscribing witnesses.

ADAM C. SMITH.

Witnesses:

JOHN WHITE,
C. B. PRICE.
